OSCAR TERVO, OF WEST QUINCY, MASSACHUSETTS.

CRANBERRY-PICKING MACHINE.

1,323,928.

Specification of Letters Patent.

Patented Dec. 2, 1919.

Application filed July 15, 1918. Serial No. 244,966.

To all whom it may concern:

Be it known that I, OSCAR TERVO, a citizen of Russia, residing at West Quincy, in the county of Norfolk and State of Massachusetts, have invented certain new and useful Improvements in Cranberry-Picking Machines, of which the following is a specification.

This invention relates to harvesters, and more especially to berry pickers; and the object of the same is to produce a machine for gathering cranberries. As is well known to those engaged in this business, cranberries grow on vines in bogs and are now ordinarily picked by hand by means of scoops. A scoop has a bottom made of fingers, a rigid top connected at its rear end with the base of said fingers and diverging thence from them toward their tips, and a stop board movably mounted so that it may be passed across the mouth of the scoop which is the space between the free edge of the top and the tips of the fingers. The latter are run through the vines; then the stop board is depressed to close the mouth of the scoop, and then the entire scoop is lifted to pick the berries from the vines, leaving comparatively few leaves within the scoop. The charge of material thus collected is then dumped into a receptacle and carried to a remote point, where it is subjected to separator treatment to remove the leaves and vines and leave only the berries. I propose to construct a machine having wheels of broad tread so that they will travel successfully over boggy ground, and equipped with moving scoops of substantially the construction above described, with means for closing the scoops at proper points, with devices for stripping the charge from the scoops at another point when they are opened, and with a carrier and elevator for collecting the charge so stripped from the scoop and delivering it at a single point.

The features of this invention may be said to be those which carry out the idea thus broadly stated, and for details of the preferred construction of my invention reference is made to the following specification and claims and attention is invited to the accompanying drawings wherein:

Figure 1 is a plan view of this machine complete, with parts of the framework broken away,

Fig. 2 is a longitudinal sectional view through the several scoops and the mechanism for carrying them and for opening and closing them, and a cross section through the stripping and carrying mechanism which stands transverse to the gathering mechanism,

Fig. 3 is an enlarged sectional detail through the track on the line 3—3 of Fig. 2,

Fig. 4 is an enlarged side elevation of one of the scoops,

Fig. 5 is an enlarged plan view of one of the scoops, partly broken away,

Fig. 6 is an enlarged sectional detail of one of the combs and one of the carriers, taken on about the line 6—6 of Fig. 2.

The main frame 1 is mounted on two rear wheels 2 and a front wheel 3 which is capable of being turned by the steering mechanism 4 and a hand wheel 5 adjacent the driver's seat 6; and although I have shown but a single front wheel it is obvious that a pair of front wheels might be employed. For motive power I preferably use a small gasoline engine 7 whose power shaft 8 is connected by sprockets and chains 9 with the main axle 10 as seen only in Fig. 1. The control levers and other details of the engine are omitted. The main frame carries a sub-frame 11 in which most of the mechanism yet to be described is located and supported, but in this specification I will not elaborate details of the framework, bearings, carrier, elevator, et cetera. The power shaft 8 is connected by gears 12 with a longitudinal shaft 13 as seen in Fig. 1, and this in turn is connected by gears 14 with a cross shaft 15 mounted in the sub-frame. The cross shaft in turn is connected by sprockets and chains 16 with the shaft 17 of the lower roller of an endless belt moving upward in an elevator 18, and the shaft 17 is connected by gearing 19 with the carrier shaft 20 best seen in Fig. 6. I do not wish to be limited, however, to this preferred means of conveying power from the main shaft 8 to the several mechanisms yet to be described, but the illustration with this brief description will suffice to set forth one means for attaining the end desired.

The gathering mechanism described below includes a pair of chains carrying a series of scoops, a second pair of chains for

holding the scoops ever horizontal, and means for opening and closing them at times. Large sprocket wheels 21 are mounted fast on the cross shaft 15 and smaller 5 upper and lower sprocket wheels 22 and 23 on stub-shafts inside the sub-frame 11 near the rear end of the latter, and around these sprockets move endless chains 24 which will be called the power chains. What may well 10 be called track chains 25 co-act with the power chains and move over front tracks 26 and rear tracks 27. The upper and lower stretches of the two pairs of chains are parallel and horizontally coincident, al- 15 though the track chains are outside the power chains as seen in Fig. 1. At the front of the gathering mechanism as seen at the left of Fig. 2 the tracks 26 bow forward of the front sides of the sprocket wheels 21, and at the rear of the gathering mechanism the tracks 27 are also at the forward side of the upwardly rising stretch of the power chains as there shown. In other words, at the front and rear the tracks are 20 forward of the corresponding stretches at the front and rear of the power chains. 25

Each scoop (see Figs. 2 and 4) has a slatted bottom made up of a number of teeth or fingers 30 inclining downward and 30 rearward from the front end, a fixed and closed top plate 31 extending rearward and horizontally from said front end, two side arms 32 pivoted at their forward ends to the front end of the body, and a lip 33 carried 35 by and depending from the rear ends of said arms and adapted when depressed to close the mouth of the scoop which is that portion between the rear extremities of its top plate 31 and fingers 30. At each end of the 40 body is a crank arm as best seen in Fig. 5, and the shank 34 of each crank arm is connected with a power chain 24, while the crank pin 35 is connected with a track chain 25. The result is that the pin travels forward of 45 the shank and ever in horizontal alinement therewith so that the general line of the scoop is horizontal, and while the shanks 34 are passing around the large sprockets 21 the pins 35 are passing around the front tracks 26; and also while the shanks 34 are 50 traveling around the small sprocket wheels 22 and 23, the pins are traveling in the rear tracks 27. I speak of the scoops as being substantially horizontal, but it is their top plates which are horizontal while their fingers 30 incline rearwardly a little as seen, but when the lip 33 is closed the material within the scoop cannot run out, despite such inclination of the fingers. In stand- 55 ards or bearings 36 rising from the top plate of each scoop is mounted a shaft 37 whose extremities have cranks 38 which project between oppositely acting springs 39 disposed within slotted boxes 40 mounted on the arms

32. The springs oppose each other and hold 65 the cranks 38 normally centered within said boxes, and when the arms 32 are raised as seen in Fig. 4 they are held raised, whereas when said arms are depressed by any means which give the cranks 38 a half revolution, 70 the counteracting force of the springs will hold the cranks depressed and the arms down. Therefore such structure will hold the lip of each scoop either up or down as desired, but will not permit it to stop at 75 an intermediate position. The driving connection between the power shaft 8 and the cross shaft 15 which carries the large sprocket wheels 21, is such that the power chains 24 and the series of scoops move more 80 rapidly to the rear than the machine travels over the ground, and the open mouths of the scoops are carried rearwardly through the vines while the machine is progressing along the bog. In order to gather in the 85 berries each scoop opens as it moves to the rear, at the bottom, as indicated by the arrow in Fig. 2; then, before it begins to ascend on the rear tracks 27, the cranks 38 strike lugs 41 and are given a half revolution 90 so that the scoop is closed, and it remains closed during its passage around the lower sprocket wheels 23 and around the upper sprocket wheels 22 as seen at the right of Fig. 3. Having passed the upper 95 sprocket wheels, the cranks 38 strike other lugs 42 whereby the arms and lip are raised and the mouth of the scoop is opened again, and it remains open while it passes around the remainder of its elliptical path. Therefore the charge of material gathered along the bottom stretch of chains is delivered at a point along the top stretch, while the automatic closing of the scoops and automatic opening thereof is produced through 100 the instrumentality of the cranks 38 and lugs 41 and 42. These lugs are carried by brackets 42 connected with the main frame and one of which is shown at the top of Fig. 1. The gathering mechanism having 105 thus performed its work, means are necessary to receive the berries picked, and we pass to the next feature of the invention. 110

A carrier is supported within the main frame, its casing 50 being disposed transversely thereof as seen in Fig. 2 and extending completely through the two pairs of chains in rear of the driving sprockets 21. This carrier is made up of preferably three endless aprons 51 moving around idle rollers 52 at the right side of the machine and power rollers 53 at the left side of the machine on the shaft 20, and it will be understood from Fig. 1 that the carrier conveys the material through the main frame and 115 delivers it to the elevator. The latter raises it alongside the machine and delivers the material into a hopper, or into a bag at 120

tached beneath the upper end of the elevator for this purpose; or it might be possible to drive a wagon alongside and permit the elevator to deliver into that. These details 5 are not necessary to the present invention. The carrier underlies that portion of the gathering mechanism where the scoops are successively opened, as will be seen in Fig. 2; and for the purpose of stripping all the

10 material out of each scoop in case it should become clogged therein, I provide a series of combs as seen in Fig. 6. If there are three carrier aprons as shown, there will be three combs, one just forward of each apron, 15 and by preference these combs will be actuated successively as described below.

Within the casing 50 is mounted a guide which may well be made of tubing as seen at 60, the same rising from the bottom of 20 the casing and standing between the idler rollers 52 at one side and the power rollers 53 at the other side. The top of the guide is provided with upright openings 61 in which are guided upright teeth 62 constituting the comb and mounted on a transverse 25 comb head 63. From the latter rigidly depends a stem 64 working in an upright guide 65 which has a slot at one side as seen at 66. A comb lever 67 projects through 30 this slot and engages a pin 68 in the side of the stem, the lever being moved from time to time by the action of a cam 69 which is rotated through gears 69' connecting it with the shaft 20. One appropriate means of 35 forming the lever and the cam is shown in Fig. 6, but I do not wish to be limited at all in this connection, and therefore it will not be necessary to describe the same. It is sufficient to say that at appropriate moments the cam and lever cause the rise of the 40 pin and comb, and the teeth 62 of the latter are projected through the guide openings 61 as seen at the left of Fig. 2 so that they pass between the fingers 30 in the scoop 45 which is at that time above the carrier, and the material within this scoop is stripped out of it and permitted to drop onto the apron 51. The parts will be so timed that as the next succeeding scoop comes over 50 the carrier casing 50, it is the second comb which rises and strips the contents out of it; then the next succeeding scoop will be actuated by the third comb, and thereafter the cycle is repeated and the following 55 scoop is treated again by the first comb. For this reason the material is delivered successively onto the several aprons of the carrier, and the latter does not become choked. These aprons convey the material 60 to the elevator 18, for treatment as above suggested. As the general operation of this machine has been given in connection with the description of its several features, I will not repeat it here.

The foregoing description and the drawings have reference to what may be considered the preferred, or approved form of my invention. It is to be understood that I may make such changes in construction and arrangement and combination of parts, 65 materials, dimensions, et cetera, as may prove expedient and fall within the scope of the appended claims.

Having thus fully described my invention, what I claim as new and desire to 70 secure by Letters Patent is:—

1. In a cranberry gatherer, a scoop having a fixed top, a bottom composed of fingers diverging from the top from the front toward the mouth of the scoop at the rear, 75 arms pivotally connected with said top at their front ends, and a lip carried by said arms for closing said mouth; combined with means for moving said scoop through the vines to gather the berries, means for mechanically closing said lip and raising the scoop out of the vines, and means for mechanically opening the lip to dump the berries. 80

2. In a cranberry gatherer, a scoop having a fixed top, a bottom composed of fingers diverging from the top from the front toward the mouth of the scoop at the rear, arms pivotally connected with said top at their front ends, and a lip carried by said arms for closing said mouth; combined with 85 endless chains for moving the scoop horizontally through the vines for gathering the berries, and means adjacent said chains for opening the lip before such movement, closing it after the berries are gathered and while the scoop is ascending at the rear of said endless chains, and opening the lip at a point in the upper stretch of the chains, for the purpose set forth. 90

3. In a cranberry gatherer, a scoop having a fixed top, a bottom composed of fingers diverging from the top from the front toward the mouth of the scoop at the rear, arms pivotally connected with said top at 95 their front ends, and a lip carried by said arms for closing said mouth; combined with endless chains of like formation for moving said scoop horizontally through the vines and gathering berries and then raising the scoop and carrying it back to the beginning of its second stroke through the vines, means on the scoop for raising and lowering the arms to open and close the lip, and lugs engaged by said means at certain points in 100 the travel of the scoop near the rear of the frame, as described. 115

4. In a cranberry gatherer, a scoop having a fixed top, a bottom composed of fingers diverging from the top from the front toward the mouth of the scoop at the rear, arms pivotally connected with said top at 110 their front ends, and a lip carried by said

arms for closing said mouth; combined with bearings on said lip, crank-arm on said arms, opposed springs in each box, a shaft journaled in said bearings and having cranked ends projecting through the boxes between the springs therein, means for moving the scoop, and lugs with which the projecting ends of the cranks engage for raising and lowering said arms and opening and closing the mouth of the scoop at intervals, as described.

5. In a cranberry picker, the combination with a series of scoops whereof each comprises a body having a normally open mouth at its rear end and a slatted bottom, a movably supported stop plate for closing said mouth, and at each end of said body a crank whose shank projects therefrom at one point and whose crank pin projects 10 from the arm at another point; of a pair of endless power chains with which said shanks are connected at intervals, another pair of chains with which said pins are connected at like intervals, spaced wheels carrying 15 the first-named chains through a substantially elliptical path, and tracks carrying the second-named chains through a path of corresponding shape except that its front and rear stretches are disposed forward of 20 the corresponding stretches of the other path, for the purpose set forth.

6. In a cranberry picker, the combination with a series of scoops whereof each comprises a body having a normally open mouth 25 at its rear end and a slatted bottom, a movably supported lip for closing said mouth, and at each end of said body a crank-arm whose shank projects therefrom at one point and whose crank pin projects from the 30 crank at another point; of a pair of endless power chains with which said shanks are connected at intervals, another pair of chains with which said pins are connected at like intervals, a pair of large sprocket 35 wheels at the front end of the first-named chains and two pair of small sprocket wheels at the rear end thereof whereby the chains are caused to travel around a substantially elliptical path, a pair of tracks adjacent the 40 large sprocket wheels, outside the same respectively, struck on curves corresponding with the curvature of the front sides of these 45 wheels, and advanced beyond said sides, and a pair of tracks similarly disposed with 50 respect to the rear sprocket wheels and advanced with respect to their rear sides, the horizontal stretches of all such chains being substantially coincident transversely thereof 55 whereby all scoops will be held with their top plates ever horizontal.

7. In a cranberry picker, the combination with chains moving through a substantially elliptical path, a series of scoops mounted on said chains and having slatted bottoms

inclining rearward to their mouths, and 65 lips for closing and opening said mouths; of a carrier disposed transversely through said chains, and stripping mechanism at the forward side of said carrier including teeth projecting through the bottoms of the 70 scoops.

8. In a cranberry picker, the combination with chains moving through a substantially elliptical path, a series of scoops mounted on said chains and having slatted bottoms 75 inclining rearward to their mouths, and means for closing and opening said mouths; of a carrier disposed transversely through said chains, and at the forward side of said carrier a comb comprising an upright stem, 80 a transverse comb head, and a plurality of upright teeth shaped to enter the slots in the bottom of each scoop as it passes over the comb, for stripping the material out of the same while its mouth is open.

9. In a cranberry picker, the combination with chains moving through a substantially elliptical path, a series of scoops mounted on said chains and having slatted bottoms inclining rearward to their mouths, and 90 means for closing and opening said mouths at intervals; of a carrier movable transversely through said chains and comprising a plurality of spaced carrier aprons, a stripper at the front edge of each apron comprising a comb having upstanding teeth, and means for raising and lowering the comb at will.

10. In a cranberry picker, the combination with chains moving through a substantially elliptical path, a series of scoops mounted on said chains and having slatted bottoms inclining rearward to their mouths, and means for closing and opening said mouths at intervals; of a carrier movable 100 transversely through said chains and comprising a plurality of spaced carrier aprons, a guide disposed along the front edge of each apron and having upright openings, a comb head underlying the guide and having 105 upright teeth passing loosely through said openings, a stem depending rigidly from said head, a lever connected with said stem for raising and lowering the comb, and a cam for actuating said lever, the cam being 110 timed to raise the comb as a scoop is passing over it.

11. In a cranberry picking machine, the combination with endless chains moving in a substantially elliptical path, and gathering means carried thereby; of a carrier disposed transversely through the chains, stripping means for transferring the material gathered onto the carrier, and delivering 120 means to which the carrier delivers.

12. In a cranberry picking machine, the combination with endless chains moving in a substantially elliptical path, and gathering

ing means carried thereby; of a carrier disposed transversely through the chains, stripping means for transferring the material gathered onto the carrier, an elevator to
5 which said carrier delivers, a main frame mounted on wheels and carrying all instrumentalities, and means for driving them.

In testimony whereof I affix my signature in presence of two witnesses:

OSCAR TERVO.
